UNITED STATES PATENT OFFICE.

GUY P. THURBER, OF PITTSBURGH, PENNSYLVANIA, ASSIGNOR, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

TRAIN-CONTROL SYSTEM.

1,200,048.

Specification of Letters Patent.

Patented Oct. 3, 1916.

Application filed May 20, 1912. Serial No. 698,388.

To all whom it may concern:

Be it known that I, GUY P. THURBER, a citizen of the United States, and a resident of Pittsburgh, in the county of Allegheny and State of Pennsylvania, have invented certain new and useful Improvements in Train-Control Systems, of which the following is a specification.

The invention relates in general to those automatic systems of train control wherein the train is brought under automatic control when danger conditions exist.

The objects of the invention may be stated to be to improve upon these systems and render them more practical and efficient in actual use.

One feature of the present invention consists in combining an automatic train controlling system with the air brake system of the train so that when the train enters a danger zone the brakes will be automatically applied and the motive power will be cut off. The means for accomplishing this purpose may vary. Preferably the brakes are applied when the train enters the danger zone by means of what I have termed an automatic brake valve which is actuated to release pressure in the train line to cause the setting of the brakes. This automatic brake valve is preferably interposed in between the engineer's brake valve and the point of connection with the train line, and is so arranged that when operated, it not only provides an exhaust passage for the train line pressure but also cuts off communication between the engineer's valve and the train line, thereby taking control of the train out of the engineer's hands.

In connection with this automatic brake valve another feature of the invention consists in providing certain means whereby the engineer, though unable to release the brakes, may, when the automatic means has taken control of the train, if he finds it necessary, still further facilitate and hasten the quick application of the brakes.

Numerous other features and objects of the invention will appear as the specification proceeds.

In the drawings I have illustrated a preferred embodiment of the invention but I would have it understood that various changes and modifications may be made

therefrom without departing from the spirit and scope of the invention.

In the drawings: Figure 1 is a more or less diagrammatic representation of the air brake equipment of a locomotive and so much of an automatic train controlling system as is necessary to properly illustrate the invention. Fig. 2 is a longitudinal sectional view of the automatic brake valve, with the parts shown in their normal position. Fig. 3 is a like view of the same with the parts shown in the operative position assumed when an automatic application of the brakes is made. Fig. 4 is a longitudinal view of the compound valve which controls the operation of the automatic brake valve and the throttle valve.

Like reference characters refer to like parts throughout the several views.

The drawings show only so much of the air brake system and the automatic train controlling system as is needed to illustrate the correlation of the two.

Referring particularly to Fig. 1, 1 designates the train line, 2 the engineer's valve and 3 the main reservoir or other source of fluid pressure of the air brake system, while 4 designates the automatic brake valve and 5 the device in the automatic train controlling system which controls the operation of the automatic brake valve. The air brake system may be of the usual type in which the brakes are applied by reducing the pressure in the train line, the rate and the extent of reduction in the train line determining the force and rapidity at which the brakes are applied. Ordinarily the application of the brakes is wholly under the control of the engineer by means of his controlling valve 2 in the usual way. But when the train enters a danger zone, the control is taken out of the engineer's hands and the train is brought under automatic control. The automatic brake valve is the means by which the control of the train is removed from the engineer and rendered automatic. The brake valve is therefore preferably interposed at a point between the engineer's valve and the train line, preferably by placing it in the line of piping extending between the engineer's valve and the train line.

By referring to the sectional views, it

will be seen that the brake valve has a main passage 7 therethrough which when open provides free communication between the engineer's valve and the train line. Controlling this main passage there is a cut off valve 8, and means are provided for holding this cut off valve open under normal conditions, and for closing it when the automatic train controlling system acts.

10 Different means may be employed for operating the automatic brake valve but preferably the means for this purpose is in the form of a pressure-actuated device, such as the piston 9 which works within a cylinder 10 and carries the valve rod 11 on the end portion of which the cut off valve 8 is mounted. In the embodiment illustrated when fluid under pressure is admitted to the head of the piston, the same will be 15 actuated to open the cut off valve to permit free passage between the engineer's valve and the train line. The parts might, however, be arranged in reverse relation so that when pressure is admitted to the piston the 20 cut off valve will be closed. With the form illustrated a spring 12 is preferably employed to carry the cut off valve into firm engagement with its seat 13 when the pressure upon the piston is relieved. Extending 25 from the side of the brake valve which is connected to the train line, there is an exhaust passage 14, which passage is, in the normal position of the parts, closed by an exhaust valve 15. It is intended that when 30 the cut off valve is closed the exhaust valve shall be open and vice versa. Accordingly the exhaust valve is preferably also carried by the valve stem 11 in the manner indicated.

35 In order that the operation of the parts so far described may be fully understood, attention is directed particularly to Fig. 1. There the device 5 is a valve which controls flow of the actuating fluid to the piston of the automatic brake valve. The valve 5 is 40 under the control and in fact forms a part of the automatic train controlling system which is partly shown in this view. Ordinarily this valve 5 is energized and serves 45 to permit flow of pressure to the piston of the automatic brake valve whereby the piston acts to hold the exhaust valve closed and the cut-off valve open, the actuating fluid being conveyed from the valve 5 to the 50 piston of the automatic brake valve through suitable piping 16. This valve which thus controls the operation of the automatic brake valve, serves when it is deenergized, to release the pressure under the piston 9 of 55 the automatic brake valve, whereupon the valve rod is shifted over to close the cut-off valve and to open up the exhaust valve, as indicated in Fig. 3. The closing of the 60 cut-off valve cuts off communication between the engineer's valve and the train line

and the simultaneous opening of the exhaust valve provides a means of escape for the pressure in the train line through the exhaust passage 14 and out through the exhaust port 17. The release of the air in the 70 train line causes the setting of the brakes in any well known manner. In the illustration the reduction in pressure in the train line actuates the triple valve 18 which opens up flow of the fluid under pressure 75 from the auxiliary reservoir 19 to the brake cylinders 20. The valve 5 illustrated in detail in Fig. 4 is under the control of the automatic train controlling system and acts under certain conditions which the automatic train controlling system is capable of 80 taking cognizance of. For instance this might be a danger valve which would be deenergized upon the train entering a danger zone and would then, by its action 85 described above, cause an emergency application of the brakes to be made through the medium of the automatic brake valve. The pressure which is normally maintained under the piston in the automatic brake 90 valve, may be ordinarily supplied from the high pressure reservoir 3 through the piping 21.

When the brakes are applied in the manner above set forth, it is desirable that the 95 motive power should also be shut off. Accordingly there is preferably provided a throttle controlling cylinder 22 arranged so that when pressure is admitted to it through the piping 23, it will, acting upon 100 the throttle lever 24, close the throttle. Flow of fluid under pressure to the throttle controlling cylinder is preferably governed by the same valve which controls the operation of the automatic brake valve. The 105 valve 5 is, therefore, preferably like the magnet valve disclosed in my application Serial No. 632,052, which acts to open up fluid under pressure at one point and to release the fluid under pressure at another 110 point.

In its preferred form the compound control valve illustrated in Fig. 4 consists of a valve casing 35 provided with an inlet port 36 communicating with the reservoir pipe 115 21. At 37 is an outlet port communicating with the pipe 23 leading to the throttle actuating mechanism and through which pressure may be supplied when the supply 120 valve 38 is raised from its seat as shown. In this position the fluid pressure flows from the port 36, through the passage 39, chamber 40, port 41, chamber 42, and thence through the passage 43 and pipe 23 to operate the throttle closing mechanism 22. The 125 valve 38 is carried on a diaphragm 44 which also carries the disk 45 mounted closely adjacent the lower face of the diaphragm 46. The diaphragm 40 has a much greater area than has the diaphragm 44 and, in the 130

normal condition of the device, fluid pressure is supplied to the upper surface of the larger diaphragm 46 and is continuously supplied to the under surface of the smaller diaphragm 44. By the differential effect thus produced the larger diaphragm moves the valve 38 to its seat in the port 41, against the opposing resistance of the smaller diaphragm 44 and normally holds 10 the valve seated. In order to unseat the valve and thereby supply pressure to operate the throttle closing device, the double acting valve 47-48 is provided. The upper member of this valve is normally held seated to close the exhaust passage 58 by its connection 49 to the armature 50 of the magnet 51. Upon a deenergization of this magnet the spring 52 operates to raise the valve 47 from its seat and to move the valve 20 48 against its seat. When the lower valve is unseated, in the normal condition of the device, fluid pressure is supplied from the port 36 through the passage 53, port 54 and passage 55 to the chamber 56 and the 25 upper surface of the diaphragm 46. Pressure is also supplied to the pipe 16 through the port 57 whereby the brake valve is normally held in inoperative condition. Upon a deenergization of the magnet 51 the connection between the passage 53 and the 30 passage 55 is closed by the seating of the valve 48, and a connection is established between the passage 55 and the exhaust port 58 leading to the atmosphere. In this condition of the device the pressure in the chamber 56 and the pipe 16 will be exhausted and the brake valve will be operated. Also the 35 valve 38 will be raised by the pressure still existing under the diaphragm 44 so that air will be supplied to the pipe 23 to close the throttle. When the parts are restored again to normal and the valve 38 is seated, the valve 59 which has a mechanical connection with the supply valve 38, is unseated and a passage thereby established 40 for the exhaust of pressure from the pipe 23, through the port 37, passage 60, chamber 61, passage 62, and exhaust port 63.

I have shown above how when the automatic brake valve is actuated, the brakes will be applied and the control of the train will therefore be taken out of the hands of the engineer. As the operation of the automatic brake valve takes place only in cases 50 of emergency, the parts are preferably so designed that the release of the train line pressure by the automatic brake valve will be so sudden as to obtain a so-called "emergency" application of the brakes. It is possible under certain circumstances that the 55 engineer might, if it were in his power, be able to assist the automatic controlling mechanism in securing a more sudden application of the brakes, and for this purpose I 60 propose to provide means which, while not

giving the engineer power to release the brakes while the automatic train control is in operation, will, nevertheless, give him the power to assist the automatic train control mechanism in applying the brakes more rapidly. In the preferred construction this latter means consists of a bypass 25 extending, as shown in Figs. 2 and 3, from one side around to the other side of the partition 26, which is interposed in the passage 7 of the automatic brake valve. A check valve 27 is placed in this bypass and is arranged to open upwardly or toward the engineer's brake valve, as shown. This check valve prevents the passage of any fluid under pressure from the engineer's brake valve through the bypass to the train line. When, however, the cut off valve has been closed and the exhaust valve has been opened to exhaust the train line, this check valve provides a means of escape from the train line back to the engineer's valve. It will be evident therefore that the engineer in such a case by throwing his valve to the "emergency" position can reduce the 75 pressure at the engineer's valve to zero or practically so, in which case the check valve will open to provide an additional means of escape for the train line pressure, thereby hastening the setting of the brakes. 80

It will now be understood from the foregoing how my invention provides for automatically bringing the train to a stop when the train enters a danger zone, entirely independent of any action on the part of the engineer. But in addition to this it is desirable that some warning should be conveyed to the engineer to let him know that the train is approaching the danger zone. Accordingly another feature of the invention consists in the provision of means for conveying a cautioning signal to the engineer before the train enters the danger zone. The means for imparting the caution signal may, and preferably does consist, as shown 90 in the accompanying drawings, of a so-called caution valve 28 forming a part of the automatic train controlling system. This caution valve is normally held energized by means of a circuit indicated by the 95 wires 35 and is, as shown, preferably connected with the train line pressure by piping 29. According to the preferred operation, when the train enters a caution zone, the magnet valve 28 is deenergized by the 100 rupture of the circuit indicated by 35, whereby the valve is opened and pressure from the pipe 29 flows to the time switch 30 by way of the pipe 31. The time switch is connected by means of the wires 36 to magnet valve 105 5 and normally holds the latter energized. When fluid pressure is admitted to the time switch 30, the contact member 32 is moved 110 over into engagement with the contact 33, thereby deenergizing the valve 5, causing 115 120 125 130

the latter to close off air supply to the brake valve 4 and to open up air supply to the throttle controlling cylinder 22.

In accordance with well-known devices, such as is shown in Patent No. 909,083, when the caution valve 28 is deenergized, a signal may be displayed in the cab, and again when the brakes are applied another signal may be displayed in the cab.

16 It will be understood that when the caution magnet valve 28 is opened, there is no reduction of pressure in the train line because the fluid is not exhausted to the atmosphere but is merely admitted to the time switch 30.

18 What is claimed, is:

1. The combination with an air brake system including a train line, a reservoir, and an engineer's valve interposed in the piping 20 between the reservoir and the train line, of an automatically operated valve interposed in the piping between the engineer's valve and the train line to control pressure in the train line independent of the control exercised by the engineer's valve to render the engineer's valve ineffective for retaining pressure in the train line upon the closing of the automatic valve, means for maintaining the engineer's valve constantly effective 25 to decrease pressure in the train line, and pressure operated mechanism for actuating said automatic valve.

2. In an air brake system the combination with a train line, a reservoir, a supply 35 pipe connecting the reservoir and the train line, and an engineer's valve interposed in the said supply pipe, of a normally open valve interposed in the supply pipe between the engineer's valve and the train line to 40 render the engineer's valve ineffective for retaining pressure in the train line upon the closing of the automatic valve, means for maintaining the engineer's valve constantly effective to decrease pressure in the train 45 line, means for closing said valve to cut off the air pressure from the reservoir between the engineer's valve and the train line, said valve arranged when closed to provide a means of escape for the pressure in the train line, and means controlling the operation 50 of the valve aforesaid.

3. In combination with an air brake system including a main reservoir, a train line and a controlling valve interposed between 55 the main reservoir and the train line, a brake valve interposed between the controlling valve and the train line, normally open to provide communication between the controlling valve and train line, and having an 60 exhaust passage from the train line which is normally closed, operating means for the brake valve to close communication between the controlling valve and train line and open up the exhaust passage from the train line, 65 and a bypass arranged to provide communica-

cation between the train line and the controlling valve after the brake valve has been closed.

4. In combination with an air brake system including a train line and a controlling valve connected with the train line, an automatic brake valve interposed in the connection between the controlling valve and the train line to render the controlling valve ineffective for retaining pressure in 75 the train line when the brake valve is closed, means for maintaining the engineer's valve constantly effective to decrease pressure in the train line regardless of the condition of 80 automatic valve, said automatic valve being provided with an exhaust passage, valves controlling the first passage and the exhaust passage, arranged the one valve to be closed when the other is opened, a piston connected with the valves for operating the same, and 85 means controlling flow of actuating fluid to said piston.

5. In combination with an air brake system including a train line and a controlling valve connected with the train line, an automatic brake valve interposed between the controlling valve and the train line having a 90 passage providing communication between the controlling valve and train line and being further provided with an exhaust passage, valves controlling the first passage and the exhaust passage arranged the one valve to be closed when the other is opened, a piston connected with the valves for operating the same, means controlling flow of 95 actuating fluid to said piston, and a normally closed check valve forming a bypass from the train line to the controlling valve when the valve in the first passage is closed.

6. An automatic brake valve having a 105 through passage and an exhaust passage, a valve stem, valves to the through passage and to the exhaust passage carried by the valve stem and arranged to close the exhaust passage when the through passage is 110 closed, a piston carried by the valve stem, means controlling admission of fluid under pressure to said piston, a bypass to the side of the through passage arranged to permit flow past the valve in the through passage 115 when the same is closed, and a check valve in the said bypass.

7. In combination with the train line and engineer's valve of an air brake system, an automatic brake valve comprising a main 120 passage connected at one side to the engineer's valve and at the other side to the train line, a cut off valve in said passage, an exhaust passage leading from that side of the main passage which is connected to 125 the train line, a valve to said exhaust passage, a valve stem on which both said valves are arranged so that when one is open the other will be closed, means acting on the valve stem to shift the same to close the cut 130

- off valve and open the exhaust valve, a piston on the valve stem, means for supplying fluid under pressure to said piston to normally force the piston over to hold the cut off valve open and the exhaust valve closed, a bypass extending around the cut off valve to afford a passage from the train line to the engineer's valve when the cut off valve is closed, and a check valve in the said bypass.
8. In combination with an air brake system including a reservoir, a train line feeding from the reservoir, an engineer's valve for controlling the supply from the reservoir to the train line, a train-line-exhausting valve interposed between the engineer's valve and the train line, a pressure-actuated device having a rigid connection with the exhaust valve for normally maintaining said exhaust valve inoperative, a throttle controlling-cylinder, a compound valve, branch connections between the pressure actuated device and the throttle cylinder, and a supply connection between the reservoir and said compound valve, the said compound valve arranged to normally permit flow of fluid under pressure to the fluid-actuated device through one of said branch connections and to prevent flow of fluid under pressure to the throttle controlling cylinder through the other of said branch connections and being adapted to reverse said flow.
9. In combination with an air brake system including a reservoir, a train line, an engineer's valve connected in the train line for controlling pressure from the reservoir, an automatic brake valve interposed be-

tween the engineer's valve and the train line including a cut off valve normally open to provide free passage between the engineer's valve and train line and an exhaust valve normally closed to the train line, operating means arranged to close the cut off valve to close communication between the engineer's valve and train line and to open the exhaust valve to permit escape of the train line pressure through said exhaust valve, and means to be actuated by the pressure in the train line to provide communication between the engineer's valve and train line after the cut off valve has been closed to permit additional exhaust of the train line pressure by way of the engineer's valve.

10. The combination with an air brake system including a train line and an engineer's valve for normally controlling pressure in the train line, of an automatically operated valve controlling pressure in the train line to the exclusion of the control normally exercised by the engineer's valve to retain or increase the pressure in the train line, and means for maintaining the engineer's valve effective to decrease the pressure in the train line regardless of the condition of said automatically operated valve.

Signed at Pittsburgh, in the county of Allegheny and State of Pennsylvania this 11th day of May A. D. 1912.

GUY P. THURBER.
